UNITED STATES PATENT OFFICE.

OLIVER E. MAYNARD, OF ALEXANDRIA, INDIANA, ASSIGNOR TO WINDOW GLASS MACHINE COMPANY, OF PITTSBURGH, PENNSYLVANIA, A CORPORATION OF NEW JERSEY.

GLASS-DRAWING APPARATUS.

1,114,897.

Specification of Letters Patent.

Patented Oct. 27, 1914.

Application filed June 30, 1911. Serial No. 636,309.

To all whom it may concern:

Be it known that I, OLIVER E. MAYNARD, a resident of Alexandria, in the county of Madison and State of Indiana, have invented 5 a new and useful Improvement in Glass-Drawing Apparatus, of which the following is a full, clear, and exact description, reference being had to the accompanying drawings, forming part of this specification, in 10 which—

Figure 1 is a side elevation partly broken away, showing one form of my improved apparatus; Fig. 2 is a detail end elevation of the drums; Fig. 3 is a side elevation of 15 the drums and shaft, the shaft being partly broken away; Fig. 4 is a view similar to Fig. 2, showing the parts in position after capping; and Fig. 5 is a detail view of a relief valve which I prefer to employ.

20 In the drawing of glass cylinders from a bath of molten glass, such as cylinders for forming rollers to be cracked and flattened into window glass, a thick, hollow neck is first formed, and then the walls of 25 the glass are expanded outwardly to the size desired for the cylinder. The cylinder is then drawn upwardly while maintaining substantially the same diameter through the draw, in the forming of window glass 30 rollers. The forming of the neck and cap has heretofore been done by hand manipulation of the control valves for the air and this operation has required considerable skill and practice on the part of the operator. 35

My invention is designed to provide a cap-forming attachment which may be applied to drawing apparatus of this general character, and which will serve to control 40 the air supply to the interior of the article being drawn in such a way as to automatically form the cap and then proceed with drawing the cylinder, the air being properly controlled for these purposes and being 45 proportioned to the speed of the draw.

In the drawings, in which I show my invention as applied to the usual apparatus employed in drawing window glass cylinders, 2 represents an electric motor having 50 its wheel provided with a worm, which drives worm-wheel 3 on the shaft 4. On this shaft is a pinion 5, intermeshing with toothed wheel 6 on shaft 6^a, which shaft also carries a pinion intermeshing with toothed

wheel 7 on the drum shaft 8. The drum 55 shaft 8 carries the drum 9 on which winds the cable or flexible connection 26 by which the cage or elevator device carrying the blow-pipe or bait is mounted. This drum 9 consists of a winding portion 10 of relatively smaller diameter, and a tapered conical portion 11 of larger diameter, these parts being connected by a curved portion 12 of rapidly increasing diameter. These parts are grooved in the usual manner to 60 receive the cable which is secured to the smaller drum portion.

The smaller portion 10 and the portion 12 are used during the forming of the neck and cap, so that the elevator cable winds 70 on the gradually enlarging tapered portion 11 during the drawing of the cylinder portion proper. The object of the conical form is to slightly increase the speed through the draw to compensate for the gradual cooling 75 and stiffening of the glass.

In carrying out my invention, I secure to the end of the shaft 8 a small drum 13. This is shown as having an enlarged socket portion 14 held to the end of the shaft by 80 set-screw 15. This drum is preferably also of conical grooved shape and to its outer end is pivoted an arm 16 controlled by pins 16' projecting from the end of the drum. This arm has mounted at its outer 85 end, a grooved roller 17, to which the end of the cord or flexible connection 18 is secured. This flexible connection is also secured to the lever 19 of a valve 20 in the air supply pipe 21 leading to the telescopic 90 pipe system 22, supplying air to and through the blow-pipe or bait and into the cylinder being drawn.

In the form shown, the valve lever 19 is provided with a weight 23, which tends to 95 draw it toward closed position by gravity, and in the form shown the cord 18 leads over suitable pulleys or sheaves 24. The end portion of the cord is provided with a take-up device 25 of an ordinary character. 100

Fig. 2 shows the position of the arm 16 at the time when the bait has been lowered into the bath and before the start of the drawing operation. At this time, the lever arm is in position to the left and at 105 an angle to the vertical, and the air valve is only slightly open. The drawing operation is now commenced, the rope or cord 26

winding upon the small portion 10 of the larger drum. Through the first part of the first revolution of the drum, one pin, 16' which is holding the lever 16 in the position 5 shown in Fig. 2 moves over to the right, thereby releasing said lever 16. The latter is now drawn up to the vertical position shown in Fig. 1 by the action of the weight 23. During this portion of the operation, 10 the air valve slightly closes until the lever arm is in a vertical position. The opening of the valve at this time is just sufficient to keep enough air pressure in the blow pipe to prevent the glass penetrating too far into 15 the opening of the blow-pipe, and thus render it impossible to expel the portion not adhering to the inner walls of the blow-pipe with the ordinary blowing pressure at the beginning of the blowing operation. It 20 also serves to furnish sufficient air to blow the neck of the cylinder as the bait leaves the bath. The lever 16 remains in its vertical position until the other pin 16' has been carried around by the rotation of the 25 shaft, so as to contact with the opposite side of the lever. It is during this period that the neck is formed. The lever is now moved by this other pin 16' to the position shown in Fig. 4, and during this movement, the air 30 valve is being rapidly opened. In the meantime, the cord 26 has commenced to wind upon the portion 12 of the main drum, so as to increase the speed of the draw. During substantially the whole period of 35 the cap forming operation, the cable 26 is winding on the part 10 of the drum. While the cable 26 is winding over the part 12, the cord or cable 18 is winding over the smaller drum 13.

40 In lowering the bait into the bath prior to beginning the draw, the main cable 18 will be unwound on the smaller portion 10 of the drum and the lever 16 will be moved backwardly to the position shown in Fig. 2, 45 and will thus open the air valve somewhat to open up the glass from the bait. From this position of the lever to its vertical upright position, the air will be gradually decreased although not completely shut off.

50 In the use of this attachment, I have found that a smaller amount of air should exhaust during the cap-forming operation than during the drawing of the cylinder. Consequently, instead of using the ordinary 55 vent hole, which is now employed, and which is opened after the cap is formed, I employ a special valve which is provided with two openings of different sizes. The smaller opening is thrown open during the 60 cap-forming after which I draw the valve so as to open the larger opening and allow a greater exhaust during the cylinder drawing. In the form shown, I provide an escape valve 27, which is shown as mounted 65 on a branch pipe 28 leading from the main

supply pipe 21, this valve having two separate openings *a* and *b*, of which the opening *a* is smaller than the opening *b*.

The valve stem is shown as provided with lever arms connected by cords or flexible 70 connections 30 with a three-armed hand lever 29 by which the valve may be thrown to either position. This valve is shown in detail in Fig. 5. The operator will throw the valve into the position where the small 75 hole will exhaust the atmosphere during the cap-forming operation and thereafter he will throw it in position where the opening *b* will exhaust the atmosphere and allow it to remain in this position during the drawing 80 of the cylinder proper.

The advantages of my invention will be obvious to those skilled in the art, since the hand regulation of the air and the forming 85 of the cap by manipulation of the speed of the cage and the air are avoided, and thus the amount of labor is greatly lessened.

With my improved attachment one operator may tend to several machines. The cost 90 of the product is thus considerably decreased and the operations are made more accurate and uniform. Other factors being the same, cylinders will be formed of approximately the same size. By the provision of means such as the drum 13 having an increasing 95 diameter proportional to the increasing diameter of the drum 9, the increase in air supply can be made proportional to the increase in the drawing speed. This is an important, and I believe, broadly novel feature. 100

Many variations may be made in the form and arrangement of the apparatus without departing from my invention, since I consider myself the first to devise an automatic attachment for forming the cap in drawing 105 hollow glass articles.

I claim:

1. In apparatus for the manufacture of drawn glass cylinders, the combination with 110 a blow pipe or bait, of actuating mechanism therefor, said pipe having a control valve, and connections between the actuating mechanism and the control valve for automatically moving the valve, said connections comprising means which effect a relatively 115 slight opening of the valve during the formation of the neck portion of the cylinder, a rapid opening of the valve during the cap-forming period, and a gradual opening thereof during the formation of the cylinder proper, said actuating mechanism having means for controlling the drawing speed 120 of the blow pipe or bait in timed relation to changes in the position of said valve; substantially as described.

2. In apparatus for the manufacture of drawn glass cylinders, the combination with 125 a blow pipe or bait, of actuating mechanism therefor, said pipe having a control valve, and connections between the actuating mech-

- anism and the control valve for automatically moving the valve, said connections comprising means which effect a relatively slight opening of the valve during the formation of the neck portion of the cylinder, a rapid opening of the valve during the cap-forming period, and a gradual opening thereof during the formation of the cylinder proper, said actuating mechanism having means for controlling the drawing speed of the blow pipe or bait to give an increase in speed thereof proportional to the increased opening of the air control valve during the formation of the cylinder proper; substantially as described.
3. In apparatus for the manufacture of drawn glass cylinders, the combination with a blow pipe or bait, of actuating mechanism therefor, said pipe having a control valve, and connections between the actuating mechanism and the control valve for automatically moving the valve, said connections comprising means which effect a relatively slight opening of the valve during the formation of the neck portion of the cylinder, a rapid opening of the valve during the cap-forming period, and a gradual opening thereof during the formation of the cylinder proper, said actuating mechanism having means for controlling the drawing speed of the blow pipe or bait in timed relation to changes in the position of said valve, together with a supply connection for said blow pipe or bait, said connection having a relief port and a relief valve controlling said port, said valve having means for permitting the escape of less air during the cap-forming period than during the formation of the cylinder proper; substantially as described.
4. In apparatus for drawing glass cylinders, a blow pipe or bait, and an air supply connection therefor, said connection having a relief valve, and said valve having two definite operating positions, one of said positions, which gives a relatively small relief opening, being for use while drawing the

cap portion of a cylinder, and the other position, which gives a relatively large relief opening, being for use while drawing the body portion of the cylinder; substantially as described.

5. In apparatus for drawing glass cylinders, the combination with a blow pipe or bait, of actuating mechanism therefor, an air supply leading to said pipe, a control valve for the air, and connections between the actuating mechanism and the control valve for automatically moving said valve, said connections comprising mechanism effecting a relatively slight opening of the valve during the formation of the neck portion of the cylinder and an automatic rapid opening of the valve during the cap-forming period, said actuating mechanism having means for controlling the drawing speed of the blow pipe or bait in timed relation to changes in the position of said valve, substantially as described.

6. In apparatus for the manufacture of drawn glass cylinders, the combination with a blow-pipe or bait, of actuating means therefor, said pipe having a control valve, and connections between the actuating means and the control valve for automatically moving the valve, said connections comprising means which effect a relatively slight opening of the valve during the formation of the neck portion of the cylinder, a rapid opening of the valve during the cap-forming period, and a gradual opening thereof during the formation of the cylinder proper, and the bait or blow-pipe-actuating means having an element which gives a sudden increase in speed after the rapid opening of the air control valve, substantially as described.

In testimony whereof, I have hereunto set my hand.

O. E. MAYNARD.
